UNITED STATES PATENT OFFICE.

WALTER C. FISH, OF LYNN, MASSACHUSETTS, ASSIGNOR TO THE GENERAL ELECTRIC COMPANY, OF NEW YORK.

ELECTRIC METERING SYSTEM.

SPECIFICATION forming part of Letters Patent No. 671,272, dated April 2, 1901.

Application filed January 18, 1899. Serial No. 702,506. (No model.)

To all whom it may concern:

Be it known that I, WALTER C. FISH, a citizen of the United States, residing at Lynn, in the county of Essex, State of Massachusetts, 5 have invented certain new and useful Improvements in Electric Metering Systems, (Case No. 909,) of which the following is a specification.

Until very recently it has been the custom 10 to charge consumers of electrical current or energy supplied from central stations a certain specified price, depending upon the amount of current or energy used by each particular consumer. Each consumer has been 15 supplied usually with a recording wattmeter acting to integrate the product of current by electromotive force from instant to instant, and the charges were proportional to the readings of this instrument. Later, however, 20 it began to be realized that this system of charging was unfair both to the consumer and to the station. The cost of supplying electrical energy to a particular consumer depends not only on the amount of energy which 25 he actually does take during a given month, but also on the maximum demand which he makes upon the station. To speak more accurately, the cost of supplying energy from a station is the sum of two quantities—first, the 30 cost of being ready to supply a certain maximum load, and, second, the cost of actually supplying a certain definite load for a certain definite time. The first item contains such matters as, for example, the interest on 35 the cost of the generators, engines, &c., and the salaries of the general officers, engineers, superintendents, &c., while the second item takes account of the increased amount of coal, oil, &c., used when a large load is carried 40 for a definite time. It has therefore been proposed to place in circuit with each wattmeter a maximum - recording meter, which shall indicate the maximum demand made by the consumer upon the station during 45 a specified time and to charge the consumer a certain amount for the maximum demand which he makes and a certain additional amount for the energy which he actually uses. This system is exceedingly just 50 and satisfactory in all cases where the maximum demand is sure to occur during the

heavy-load hours; but evidently it is possible that a certain consumer may take his maximum load for a given month during the daytime, and it is unfair that in such a case 55 he should be charged heavily, since during the day the station is usually capable of supplying a load far in excess of that which it actually carries, and, in fact, is usually glad to sell current at a reduced rate. Another solution of the difficulty has been to install meters which were adjusted to read at one rate 60 during the full-load hours and at another rate during the low-load hours. This is satisfactory in certain special cases, but is sometimes objectionable, since it fails to take account of the fact that a consumer may use lights for only a very few hours each month, and thus pay only a very small bill, though 65 his load when it does come is such as to cause 70 great difficulty and annoyance to the station. An example of such a consumer would be a theater in a country town, which might be open only once a week, but which, nevertheless, would take a heavy load when the 75 station was least able to furnish it, without running up a bill in any way large enough to compensate for this objection.

My present invention contemplates overcoming the difficulties above mentioned by inserting in the consumers' circuits maximum-meters which are inoperative during the low-load hours. I further contemplate combining two-rate meters with maximum-demand meters. I further contemplate an arrangement 80 by which the same device which actuates the two-rate meter may also serve to cut in and out the maximum-demand meter. The present claims are restricted to an improved system for accomplishing these ends. The claims 85 for the mode of carrying it out are reserved for a companion application, forming a division hereof, filed January 26, 1901, Serial No. 44,777.

The accompanying drawing represents a 95 system of distribution arranged in accordance with one form which my present invention may take.

A is a source of electric current—as, for example, a generator at a central station—100 from which extend lines B C. Branch circuits leading to individual consumption-cir-

cuits are shown at D E and D' E'. Translating devices, such as lamps L L and motors W, are arranged as indicated in the consumption-circuit.

5 Referring particularly to the first of the stations shown, it will be seen that a recording-wattmeter F of the usual construction is inserted, with its field-coils in series with the mains D and its armature in multiple be-
10 tween the mains D and E. The usual resist-
ance R is placed in series with the armature, and an additional resistance S, capable of be-
ing cut out by a switch G, is inserted in se-
ries with the resistance R. In series with
15 the main D, I also insert a maximum-meter
H. This instrument is indicated here only
conventionally as consisting of an arm a, car-
rying a pencil b, moving over a scale c. A
20 solenoid d attracts the core e and pulls the
arm a downward against the action of an ad-
justable spring f. Evidently the pencil b will
trace a line, as indicated at g, upon the scale
25 c, whose length will indicate the maximum
load taken by the consumer since the scale
was renewed. Any other suitable maximum-
recording instrument may be used in place
30 of the one shown. The maximum instrument
is shunted by a switch K in such a way that
when the switch is closed the instrument will
cease to operate.

It is obvious that by suitably manipulating
the switches G and K the method above out-
lined may be carried out. As an illustration
of one manner in which this may be accom-
35 plished I have shown an additional wire M
extending through the system, with branches
N N' at the particular consumption-circuits.
Each of these branches leads through a solen-
40 oid O, which solenoid actuates an insulated
rod P against the action of a spring Q. In
the central station I arrange a switch T, which
is capable of supplying current to the wire
M, preferably through a resistance U.

The operation of the system thus described
45 is as follows: During the hours of heavy load—
for example, from five o'clock p. m. until mid-
night—the switch T is closed. Current thus
flows from the main B, through the resistance
50 U, switch T, and wire M, to the wire N, and
thence through the solenoid O to the wire E
and back to the station. The solenoid thus
energized closes the switch G and opens the
55 switch K. The result is to cut out the resist-
ance S in series with the resistance R in the
armature-circuit of the recording-meter and
to open the shunt around the maximum-meter.
The two-rate meter now runs on the high rate
60 and the maximum-meter becomes operative.
Under such conditions the customer will
naturally use as little current as possible and
will avoid taking a heavy load even for a

short time. As the load goes off from the sta-
tion the switch T will be thrown to the posi-
tion shown in the drawings. This will open-
circuit the coil O, and the spring Q will close 65
the switch K and open the switch G. The re-
cording-meter F will now run on the low rate
and the maximum-meter will be inoperative.
This will encourage customers to use current
freely at the time when the station is best able 70
to furnish it.

It will be obvious that my invention is not
restricted to the particular two-rate meter ap-
paratus shown, nor to the particular method
of control shown, as I may use, for example, 75
any of the arrangements now well known in
the art, devised by Kapp, Barstow, and Oxley.

What I claim as new, and desire to secure
by Letters Patent of the United States, is—

1. In an electric metering system, the com- 80
bination of a supply-circuit, registering-me-
ters at the consumers' stations, maximum-de-
mand meters at the consumers' stations, and
means for cutting the maximum-demand me-
ters into the consumers' circuit at determi- 85
nate hours.

2. The combination with leads from an elec-
tric supply system, of a consumption-circuit
and a two-rate meter device and a maximum
meter device in series with the consump- 90
tion-circuit.

3. The combination with leads from an elec-
tric supply system, of a consumption-circuit
and a two-rate meter device and a maximum
meter device in series with the consump- 95
tion-circuit, and means for cutting out the maxi-
mum instrument during the period of low
rate.

4. The combination with leads from an elec-
tric supply system, of a consumption-circuit, 100
a maximum instrument in operative relation
with said circuit, and means for cutting out
the maximum instrument without affecting
the supply of current to the circuit.

5. In a system of electric distribution, one 105
or more consumers' circuits supplied with in-
tegrating and maximum instruments, and
means operated from a central point for si-
multaneously varying the rate and cutting
out the maximum instrument. 110

6. The combination of a two-rate meter de-
vice and a maximum instrument in operative
relation to the same circuit, and means where-
by the normal operation of the two-rate device
cuts out the maximum instrument during the 115
period of low rate.

In witness whereof I have hereunto set my
hand this 14th day of January, 1899.

WALTER C. FISH.
